No. 716,686.

Patented Dec. 23, 1902

J. C. DICKS.

PROTECTOR FOR RAILWAY SWITCHES.

(Application filed June 16, 1902.)

(No Model.)

UNITED STATES PATENT OFFICE.

JOSEPH C. DICKS, OF WINTERTON, NEW YORK.

PROTECTOR FOR RAILWAY-SWITCHES.

SPECIFICATION forming part of Letters Patent No. 716,686, dated December 23, 1902.

Application filed June 16, 1902. Serial No. 111,940. (No model.)

To all whom it may concern:

Be it known that I, JOSEPH C. DICKS, a citizen of the United States, residing at Winterton, in the county of Sullivan and State of New York, have invented new and useful Improvements in Protectors for Railway-Switches, of which the following is a specification.

My invention has relation to improvements in railway-switches; and the object is to simplify and improve the existing art by providing a switch-protector whereby the switch-bars are shielded from the deposits of snow and other debris which under other conditions might interfere with the proper working of the movable switch points or rails.

With these objects in view my invention consists in the novel construction of parts and their assemblage or aggroupment in operative combinations, as will hereinafter be fully described and the novelty particularly pointed out and distinctly claimed.

I have fully and clearly illustrated my improvements in the accompanying drawings, to be taken as a part of this specification, and wherein—

Figure 1 is a plan view of the complete device. Fig. 2 is a transverse section through the track and the plates of the device. In the drawings similar notations designate like parts throughout the illustrations. Reference being had to the drawings, A A' designate the fixed rails of a straight track, B B' the fixed rails of a diverging track, and C C' the switch rails or points, controlling the entrance to either track. These several elements and parts may be of any of the approved constructions common in the art. The switch rails or points are united at intervals by proper rods 1, the ends of which are fixed 35 in posts or brackets 2, secured in any proper manner to the inner faces of the switch-rails. A switch-rod 3 is suitably connected with the switch-rails and by which the switch is moved into the required positions. The butt-ends 40 of the switch-rails are disposed in connection to the ends of the main rails by any proper joint, as a, which indicates a loose knuckle-joint engagement which permits the switch, with the plate, to be swung laterally in either 45 direction, as indicated in Fig. 1 of the drawings.

D designates a strong iron or steel plate set between the switch-rails and provided with

recesses 4 in its edges to set about the posts or brackets 2, as indicated in Fig. 1 of the drawings. The plate D is movable with the switch and is secured in place by bolts 5, let through the plate and the flanges of the switch-rails.

It will be perceived that the plate D constitutes a complete protection and shield for all the rods connecting the switch-rails and prevents snow or other impediments hindering or interfering with the movement of the switch. The plate also effectually prevents the liability of the switchman or other persons from getting their feet caught under the connecting-rods of the switch.

On the switch-stand side of the track is secured a plate 6, laid on the projecting ends of the ties, with its inner edge bolted to the flange of the rail, as indicated at 7, and is provided with an extension 8, which covers the switch-rod 3, as shown. The plate D is formed with a downwardly-directed flange 9, 75 which sets with its inner face against the end faces of the ties. At the other side of the track, on the projecting ends of the ties, is secured a plate 10, arranged with its inner edge on the rail-flange and is formed with a turn-down flange 11, setting against the end faces of the ties. It will be perceived that these side plates make it easy to clean the snow from the sides of the track.

Having thus described my invention, what I claim is—

1. A railway-switch protector, consisting of a plate arranged to cover the space between the switch-rails, and movable therewith.
2. A railway-switch protector comprising a plate arranged to cover the space between the switch-rails and movable therewith, and plates secured on each side of the track over the ends of the ties.
3. A railway-switch protector, comprising a plate arranged to cover the space between the switch-rails and plates on each side of the track over the ends of the ties and formed with turned-down flanges to set against the end faces of the ties.

In testimony whereof I affix my signature in presence of two witnesses.

JOSEPH C. DICKS.

Witnesses:

HARRY H. WINTER,
E. N. HARDING.
